UNITED STATES PATENT OFFICE

111,870

DESIGN FOR A PIPE BENDING TOOL

John D. Benfield, Detroit, Mich.

Application June 15, 1938, Serial No. 77,846

Term of patent 3½ years

To all whom it may concern:

Be it known that I, John D. Benfield, a citizen of the United States, residing at Detroit, county of Wayne, in the State of Michigan, have invented a new, original, and ornamental Design for a Pipe Bending Tool, of which the following is a specification, reference being made to the accompanying drawing, forming part thereof.

Fig. 1 is a side view, in perspective, of a pipe bending tool showing my new design.

Fig. 2 is a side elevation thereof.

Fig. 3 is a top plan view thereof.

Fig. 4 is a bottom plan view thereof.

Fig. 5 is an end view thereof.

I claim:

The ornamental design for a pipe bending tool, as shown.

JOHN D. BENFIELD.
